UNITED STATES PATENT OFFICE

162,265

SHIP

Walter Wiggins, Jr., Washington, D. C.

Application June 29, 1950, Serial No. 10,829

Term of patent 14 years

(Cl. D71—1)

To all whom it may concern:

Be it known that I, Walter Wiggins, Jr., a citizen of the United States, residing at Washington, in the District of Columbia, have invented a new, original, and ornamental Design for a Ship, of which the following is a specification, reference being had to the accompanying drawing, forming part thereof.

Figure 1 is a side view of a ship, showing my new design;

Figure 2 is a top plan view thereof;

Figure 3 is an underside plan view;

Figure 4 is a front view, and

Figure 5 is a rear view of the same.

I claim:

The ornamental design for a ship, as shown.

WALTER WIGGINS, JR.
